UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF WEST VIRGINIA.

AUTOMATIC FIRE-RESISTING SHUTTER.

1,081,129.

Specification of Letters Patent.

Patented Dec. 9, 1913.

Application filed March 18, 1912. Serial No. 684,387.

To all whom it may concern:

Be it known that I, EDWARD H. McCLOUD, a citizen of the United States, residing at Columbus, in the county of Franklin and State of Ohio, have invented a certain new and useful Improvement in Automatic Fire-Resisting Shutters, of which the following is a specification.

This invention relates more especially to 10 rollers for automatic fire shutters so called that are provided with a normally operative counterbalance member and a thermally controlled tension member opposing the action of such counterbalance member so that upon 15 the release of the thermally controlled tension member the shutter is caused to descend and close the opening in which the shutter is installed.

The object of the invention generally is to 20 improve the details of construction of such rollers and more particularly among others to provide means for nicely regulating the speed at which the shutter shall descend and avoid violence in the action of the parts.

25 The invention is embodied in the example herein shown and described, the features of novelty being pointed out in the appended claims.

In the accompanying drawings Figure 1 30 is a sectional view taken longitudinally of the barrel or roller, parts being shown in full. In this view the disks or tumblers used in the construction are shown in those positions they occupy when the shutter is up. Fig. 2 is a view partly in elevation and 35 partly in section to illustrate details of the thermally controlled devices, and with slight changes in the forms of other parts. Fig. 3 is a sectional view showing the position of 40 the disks or tumblers when the shutter is down. Fig. 4 is a view of the inner face of the clutch member plug. Fig. 5 is an end view to illustrate the thermally controlled devices.

45 In the views 6 designates the barrel or shutter receiving member. The shutter, designated 7, can be attached either directly to the barrel or to collars secured thereon as seen at 7^a, Fig. 2.

50 The characters 8 and 8^a designate plugs fitted in the opposite ends of the barrel. The plug 8 which is in effect a clutch member is provided at its inner side with a lug 8^b, and said plug is made circularly adjustable in the barrel by means of removable

5 screws 8^c insertible in any of a series of holes 8^d. The plug 8 is also provided with a number of holes 8^e into one of which one end of a bar or pin can be inserted to facilitate the turning of the plug in its seat in the end of 60 the barrel.

9 designates a shaft part supported in the bracket 10 and extending through the plug 8^c and into the barrel. The shaft part 9 has pinned in its outer end beyond the bracket a wheel 11; and 12 is a device for locking said wheel and shaft in the position to which they may be turned. Encircling the shaft 9 is a coil spring 13 secured at one end to a collar 14 pinned on the shaft and at the 70 other end to a collar 15 secured by screws 15^a to the barrel. The collar 15 turns on the shaft 9 and constitutes a supporting member for the barrel. The function of the spring or tension member 13 is to counterbalance 75 the shutter for operation in normal circumstances and to hold the shutter in the position to which it may be uncoiled as well as to make its operation easy. The shaft part 9 has pinned to its inner end a collar 9^a.

16 designates a second shaft part that is supported in a bracket 17^a supplemental to a main bracket 17 through which the corresponding end of the barrel extends. Said shaft part 16 extends through the plug or 85 clutch member 8 and into the barrel, its inner extremity extending rotarily into one end of the collar 9^a. Encircling the inner portion of the shaft part 16 is a coil spring, or tension member 18 wound in a direction 90 to oppose the action of spring 13. The coil spring 18 is secured at one end to the collar 9^a and at its other end to a collar 19 pinned on the shaft part 16. The shaft part 16 has secured in its outer end beyond the supplemental bracket 17^a a star wheel 20 that is engaged by a pivoted dog 21 on a long weighted lever 22 fulcrumed at 22^a, said lever being held up to latch the wheel 20 by a wire 23 containing one or more links 23^a fusible by a dangerous rise of temperature. The wire 23 is shown as connected to the shorter arm of a lever 24 fulcrumed in a small hanger 25 on the ceiling or other fixed part. Said lever has its longer arm weighted as at 24^a, so as to insure prompt release of the lever 22 when one of the fusible links 23^a is melted. The collar 19 has a disk-like 95 head or clutch member 19^a provided with a lug 19^b.

100

105

110

Loose on the shaft part 16 between the head 19^a and the plug 8 is a series of disks or tumblers 26 each provided on its opposite faces, with sector like projections or lugs 6 that are each adapted to engage or be engaged by a corresponding lug or projection of an adjacent disk or tumbler or the lug of an adjacent disk or tumbler and the lug 19^b or the lug 8^b as the case may be.

10 In practice the spring 13 is first adjusted by turning the shaft part 9 until the shutter is counterbalanced or supported by that spring in elevated position after which said shaft is locked from rotation. The shaft part 16 is then turned to place the spring 18 under tension and so as to impel the shutter downward when acting on the barrel as hereinafter described after which said shaft part is latched by the thermally controlled 15 means. This last adjustment is made with the shutter entirely raised. The screws 8^c are then removed and the plug 8 turned until all the projections or lugs from the lug 8^b to the lug 19^b are abutted, as seen in Fig. 20 1, in such a way that when the shutter is normally lowered the lug 8^b will turn first out of abutment with the contiguous lug of the adjacent disk and then into abutment with the same lug but at its opposite side. As 25 the shutter is further lowered the first disk picked up acts on the second and so on, it being intended that a sufficient number of disks shall be used to permit the necessary turns of the barrel to effect a complete closing of the shutter before the last disk operates on the lug 19^b. When, however, the shutter, being in raised position, the shaft part 16 is automatically released by the thermally controlled devices the lug 19^b impelled by the released spring 18 acts through 30 the disks on the lug 8^b, and counteracts sufficiently the counterbalancing effect of the spring 13 on the barrel to uncoil the shutter to closing position, or to permit gravity to 35 operate with a similar result according to the degree of tension at which the spring 18 may have been left.

What I claim is:

1. In a rolling fire shutter, the combination of a suitably mounted shutter-receiving member, a normally operable tension member connected with a fixed part and the shutter-receiving member, an opposing tension member connected at one end with a fixed part, releasable means for holding the other end of said opposing tension member, clutch members between said opposing tension member and the shutter-receiving member for causing said opposing tension member to act on the shutter-receiving member, said clutch members being capable of idle motion with reference to each other when the shutter is lowered from raised position.
2. In a rolling fire shutter, the combination of a suitably mounted shutter-receiving

member, a normally operable tension member connected with a fixed part and the shutter-receiving member, an opposing tension member connected at one end with a fixed part, releasable means for holding the other end of said opposing tension member, clutch members between said opposing tension member and the shutter-receiving member for causing said opposing tension member to act on the shutter-receiving member, and normally idle members interposed between said clutch members adapted to effect proximate operative connection between the clutch members in the raised position of the shutter.

3. In a rolling fire shutter, the combination of a suitably mounted shutter-receiving member, a normally operable tension member connected with a fixed part and the shutter-receiving member, an opposing tension member connected at one end with a fixed part, releasable means for holding the other end of said opposing tension member, clutch members between said opposing tension member and the shutter-receiving member for causing said opposing tension member to act on the shutter-receiving member, and normally idle members interposed between said clutch members adapted to effect proximate operative connection between the clutch members in the raised and lowered position of the shutter.

4. In an automatic rolling fire shutter, the combination of a suitably mounted shutter-receiving member, a normally operable tension member connected with a fixed part and the shutter-receiving member, an opposing tension member connected at one end with a fixed part, releasable means for holding the other end of said tension member, clutch members between said opposing tension member and shutter-receiving member for causing said opposing tension member to act on the shutter-receiving member, and a tumbler between the clutch members.

5. In an automatic rolling fire shutter, the combination of a suitably mounted shutter-receiving member, a normally operable tension member connected with a fixed part and the shutter-receiving member, an opposing tension member connected at one end with a fixed part, releasable means for holding the other end of said tension member, clutch members between said opposing tension member and shutter-receiving member for causing said opposing tension member to act on the shutter-receiving member, said clutch members being in operable contiguity in the elevated position only of the shutter.

6. In an automatic rolling fire shutter, the combination of a suitably mounted shutter-receiving member, a normally operable tension member connected with a fixed part and the shutter-receiving member, an opposing tension member connected at one end with a

fixed part, releasable means for holding the other end of said tension member, clutch member between said opposing tension member and shutter-receiving member for causing said opposing tension member to act on the shutter-receiving member, means for adjusting said opposing tension member and means for adjusting one of said clutch members to establish approximate contiguity of the clutch members at the elevated position of the shutter.

7. In an automatic rolling fire shutter, the combination of a suitably mounted shutter-receiving member, a normally operable tension member connected with a fixed part and the shutter-receiving member, an opposing tension member connected at one end with a fixed part, releasable means for holding the other end of said tension member, clutch members between said opposing tension member and shutter-receiving member for causing said opposing tension member to act on the shutter-receiving member, a tumbler between said clutch members, and means for adjusting one of said clutch members.

8. In an automatic rolling fire shutter, the combination of a suitably mounted shutter-receiving member, a normally operable tension member connected with a fixed part and the shutter-receiving member, an opposing tension member connected at one end with a

fixed part, releasable means for holding the other end of said tension member, means for adjusting said opposing tension member, clutch members between said opposing tension member and shutter receiving member for causing said opposing tension member to act on the shutter-receiving member, a tumbler between said clutch members, and means for adjusting one of said clutch members. 35

9. In an automatic rolling fire-shutter, the combination of a suitably mounted shutter-receiving member, a normally operable tension member connected with a fixed part and the shutter-receiving member, means for adjusting said tension member, an opposing tension member connected at one end with a fixed part, releasable means for holding the other end of said tension member, means for adjusting said opposing tension member, clutch members between said opposing tension member and shutter-receiving member for causing said opposing member to act on the shutter-receiving member, and means for adjusting one of said clutch members to establish their contiguity in the elevated position of the shutter. 55
